UNITED STATES PATENT OFFICE.

EDWARD POSSON, OF CHICAGO, ILLINOIS.

DOOR HOLDER.

1,425,282.

Specification of Letters Patent. Patented Aug. 8, 1922.

Application filed September 12, 1919. Serial No. 323,399.

To all whom it may concern:

Be it known that I, EDWARD POSSON, a citizen of the United States, residing at Chicago, in the county of Cook and State 5 of Illinois, have invented certain new and useful Improvements in Door Holders, of which the following is a specification.

This invention relates to a door holder, and its purpose is to provide a device particularly adapted for use with railway 10 passenger cars for holding the doors thereof in open position.

The principal object of the invention is to provide an improved overhead door 15 holder which will not interfere with the movements of the passengers of the car. Another object is to provide a door holder which has a permanent connection with the door and with the door frame, so that the 20 positive action thereof is always insured when the door is opened. A further object is to provide a door holder provided with two parts having a sliding connection with each other and provided with means adapted to 25 form a locking connection between the parts when they have moved to the relative position corresponding to the open position of the door. Other objects relate to various 30 features of construction and arrangement which will be pointed out more fully herein-after.

The nature of the invention will be understood from the following specification, taken with the accompanying drawings, in 35 which one embodiment is illustrated.

In the drawings—

Figure 1 shows a front elevation of the upper portion of a door and door casing, to which the invention is applied;

Fig. 2 shows a sectional view on the line 2—2 of Fig. 1, illustrating the door holder in end elevation;

Fig. 3 is horizontal sectional view through the door casing on the line 3—3 of Fig. 1, 5 showing a top plan view of the door holder, and illustrating by dotted lines the relative position of the parts of the door holder when the door is open; and

Fig. 4 is an enlarged transverse sectional 50 view on the line 4—4 of Fig. 1.

In the drawings, the invention is shown applied to a door 10 having an upper transverse frame member 10^a, and a door frame 11 comprising an upper transverse door sill 12 of pressed metal construction, as illustrated particularly in Figs. 2 and 4.

The door sill 12 is provided with a shoulder 12^a against which the frame member 10^a of the door is adapted to seat and the upwardly extending flanges of the door sill 60 are secured to the plates 13 of the car wall which terminate on opposite sides of a channel frame member 14.

The invention comprises a bracket 15 which is secured to the upper flange of the 65 door sill and to the parts 13 and 14, above described, by means of the transversely extending screw bolts 16 which are engaged on the opposite side of the car wall by nuts 17. The bracket 15 is provided with a depending part 15^a having two horizontally extending flanges 18 which are adapted to receive between them the rod 19 which forms one of the telescoping parts of the 70 door stop. The member 19 is pivotally connected to the flanges 18 of the bracket by a vertically extending rivet or pin 20, and it has a sliding engagement with a U-shaped stop member 21 which is secured to another rod 22 by means of a series of 75 rivets 23. When the door is in closed position, the rod 22 underlies the rod 19 and extends parallel thereto along the door sill above the upper edge of the door with the stop member 21 extending upwardly 80 therefrom around the rod 19, as illustrated, for example, in Figs. 1 and 4. A horizontal wear plate 24 of suitable material is inserted in a recess in the upper part of the 85 socket which is formed through the stop 90 member 21, and this wear plate is adapted to slide upon the rod 22. The stop member 21 is provided with a plurality of vertically extending grooves 25 with corresponding projections 25^a between them, 95 and the end of the stop member opposite the bracket 15 is provided with converging surfaces 26.

The stop member 21 is adapted to engage the leaf springs 28, which are secured to the 100 opposite end of the member 19 by means of rivets 29. The leaf springs 28 are bowed outwardly from the rod 19, and the free ends of the inner leaves thereof are bent inwardly to form the bow portions 28^a which normally 105 contact with the rod 19 and, upon relative movement of the rods 19 and 22 to the proper extent, are adapted to engage the inclined surfaces 26 on the stop member and thus slide into position engaging opposite grooves 25 in the sides of the stop member. When 110 in this position, the springs 28 hold the rods

19 and 22 against further movement. The end of the rod 22, opposite the stop member 21, is offset downwardly, as shown at 22^a, and this part of the rod is extended between 5 the flanges 30 which are formed on the upwardly extending part 31^a of a bracket 31 which is secured to the upper frame member 10^a of the door by means of screws 32. The rod 22 is pivotally connected to the flanges 10 30 by a pin 33.

When the door is in closed position, the parts assume the position illustrated in Fig. 1, with the rods 19 and 22 lying one above the other in a vertical plane above the door 15 and parallel to the upper door sill. When the door is opened, the rods 19 and 22 turn on their pivots and at the same time the rod 19 slides through the stop member 21 until the ends of the springs 28 engage the inclined surfaces 26 on the stop member. The 20 springs then spread apart and slide over the sides of the stop member until they engage the grooves 25, whereupon the parts of the door holder become relatively fixed and hold 25 the door in its open position. When it is desired to open the door, a quick movement thereof will release the springs 28 from the grooves 25 and permit the parts to be returned to the position illustrated in Fig. 1. 30 By suitably proportioning the rods 19 and 22, and by varying the proportions of the stop member 21 and the springs 28, the door may be held in any desired open position.

Although I have shown and described a 35 single embodiment of the invention for purposes of illustration, it will be understood that it may be constructed in various other forms without departing from the scope of the appended claims.

40 I claim:

1. In combination, a door, a door casing, a rod pivoted at one end on said door, a second rod pivoted at one end on said casing, a stop member secured to the other end of one of said arms, and a spring secured to the other end of the other of said arms and adapted to engage directly said stop member.

2. In combination, a door, a door casing, a 50 rod pivoted at one end on said door, a second rod pivoted at one end on said casing, a stop member secured to the other end of one of said arms, and a spring secured to the other end of the other of said arms and adapted to 55 engage said stop member, said stop mem-

ber having a recess slidably engaged by said last-named arm.

3. In combination, a door having an upper frame member, a horizontal door sill located above said frame member, a bracket secured to said frame member, a second bracket secured to said door sill, a pair of rods each pivoted on one of said brackets, a stop member mounted on one of said rods and slidably engaged by the other of said rods, and springs carried by the other of said rods and adapted to coact with opposite sides of said stop member.

4. In combination, a door having an upper frame member, a horizontal door sill located above said frame member, a bracket secured to said frame member, a second bracket secured to said door sill, a pair of rods each pivoted on one of said brackets, a stop member mounted on one of said rods and slidably engaged by the other of said rods, and springs carried by the other of said rods and adapted to coact with opposite sides of said stop member, said stop member being corrugated on its lateral sides to be engaged by 80 said springs.

5. In combination, a door, a door casing, a member pivotally connected to said door, a second member pivotally connected to said casing, a stop member secured to one of 85 said first-named members and having a slot to receive the other first-named member, and springs secured to said other member and adapted to engage said stop member automatically upon relative movement of said 90 first-named members.

6. In combination, a door, a door frame, a bracket secured to said door and extending upwardly therefrom, a rod pivoted on said bracket and extending horizontally above the 95 upper edge of the door, a second bracket secured to the door frame, a second rod pivoted to said second-named bracket and extending horizontally parallel to said first-named rod, a stop member secured to said 100 first-named rod and having a slot slidably engaged by said second-named rod, said stop member having grooves therein, and leaf springs secured to said second-named rod and having inturned extremities adapted to 105 engage the grooves in said stop member.

In testimony whereof, I have subscribed my name.

EDWARD POSSON.
